(57) **CLAIM**

I claim the ornamental design for a display tray for a shelf mounted product display device, as shown in the drawings.

DESCRIPTION

FIG. 1 is a perspective view of the display tray for a shelf mounted product display device showing our new design. FIG. 2 is a front view of the display tray for a shelf mounted product display device.

FIG. 3 is a back view of the display tray for a shelf mounted product display device.

FIG. 4 is a side view of the display tray for a shelf mounted product display device.

FIG. 5 is a top view of the display tray for a shelf mounted product display device.

FIG. 6 is a bottom view of the display tray for a shelf mounted product display device.

FIG. 7 is a perspective view of the display tray showing its surrounding environment including a shelf bracket; and, FIG. 8 is a side view of the display tray showing its surrounding environment.

The broken-line disclosure in the views is for illustrative purposes only and forms no part of the claimed design.
